HINGE PINTLE EJECTOR

William H. Johnson, 1412 Claiborne St., Danville, Va.
Filed Mar. 30, 1961, Ser. No. 99,493
3 Claims. (Cl. 29—267)

The present invention relates to a portable manually actuatable wholly mechanical-type hinge pintle dislodging and ejecting device, more particularly, a specially constructed implement or device and which is expressly, but not necessarily, designed and adapted to be used on butt hinges such as are currently being used on and in conjunction with tobacco hogsheads made up of symmetrical half-sections which are operatively joined together by butt hinges.

Stated otherwise, the concept has to do with a simple, practical and feasible tool-like device which provides an easy-to-use pintle ejector, the same serving to speed up the pintle removing step in a manner to expedite opening a hogshead, the construction being such that it promotes a saving in time and labor and ejects pins from the hinges without damage to the surfaces of the hogshead sections or the leaves of the hinges. Ordinarily, sectional hogsheads are placed on dollies in an upright position with the heads of the hinge pins up in order to make it easier to remove the pins. The present mode of accomplishing the result, not considering the advent of the instant invention, involves haphazardly knocking the pintles or pins out using hammers, hatchets and screwdrivers. Manifestly, the hinges and hogsheads are damaged from time to time. Not only this, any number of pins are "banged" out with such force that they are lost. Generally speaking workmen are not too much concerned with the factors of damage and loss. Therefore, the problem which has posed itself is one which calls for a practical and an acceptable solution. It follows that the herein disclosed invention offers a practical adaptation which provides a satisfactory solution.

Briefly, a preferred embodiment of the invention is that which is herein disclosed in the views of the drawing. By glancing at the drawing it will be seen that the improved hinge pin loosening and ejecting device is characterized by a portable base designed and adapted to be coordinated with and positioned properly over and in relation to the leaves and pintle-containing knuckles between the contiguous ends of said leaves, said base having predetermined portions thereof which are precisely alignable with the knuckles and push-out-type pintle, handle means carried by said base, plunger means connected with said base and embodying a plunger with an end to line up with said pintle so that by imposing a thrust against the pintle the latter can be dislodged and forced out of the knuckles containing it, and means for forcibly moving the rod toward and from the end of the pintle with which it is engageable.

More specifically, novelty is predicated upon a base comprising a block-like body channel-shaped in cross-section with the channel lined up with the leaves of said hinge, the longitudinal walls of the channel having registering notches said notches also being coordinated and registerable with the respective ends of said pintle, and said rod being in line with and operable through said notches.

A still further improvement resides in a channel-shaped base with an outstanding handle, guide notches in the wall of the channel, a cylindrical sleeve providing a sheath and said sheath containing a reciprocable plunger rod. The plunger rod engages the pintle and is provided with rack teeth operated by a gear having a suitable crank handle.

These together with other objects and advantages which

2

will become subsequently apparent reside in the details of construction and operation as more fully hereinafter described and claimed, reference being had to the accompanying drawing forming a part hereof, wherein like numerals refer to like parts throughout, and in which:

FIGURE 1 is a view in perspective showing a fragmentary portion of an upstanding tobacco containing hogshead, the customarily used butt hinge and showing, what is more important, the invention and how it is constructed and used;

FIGURE 2 is a view on an enlarged scale with parts in section and elevation taken on the plane of the line 2—2 of FIGURE 1, looking in the direction of the arrows;

FIGURES 3 and 4 are sections on the line 3—3 and 15 4—4, respectively, of FIGURE 2.

The hinge means as an entity is denoted by the numeral 6 and is a butt-type hinge construction, the leaves thereof being denoted at 8 and 10 and fastened in place at 12 on the component parts 14 and 15 of the tobacco containing hogshead (not detailed). The adjacent ends of the leaves are provided with the usual knuckles 16 and 17 containing the insertable and removable hinge pin or pintle 18. The pin as usual is provided with a head 19. These are all old or conventional parts. The invention resides in the improved device (tool or implement as it may be acceptably called). The base of the device denoted at 20 is a comparatively heavy one-piece metal block which may be said to be rectangular in plan and which is channel-shaped in cross-section, the web or body of the channel being denoted at 22 and the longitudinal flanges or side walls at 24 (FIG. 1). These flanges are provided with registering notches 26 and 28 (FIG. 2) which when the base is in use are lined up with the hinge pin and knuckles. Attached to at one end portion to the body of the base is an outstanding heavy metal handle 30. This handle may be secured atop the base by screws or equivalent fasteners 32 as shown in FIG. 3. The handle functions not only for lifting, lowering and positioning the base in coordinate relation, it contributes

40 to the other means for orienting the plunger. This plunger comprises a reciprocable rod 34 which is shiftable in a tubular sheath or cylinder 36 which is fixed across the lower edge portion of an adapter plate 38. This plate is a simple flat member having an end portion 40 superimposed against one side of the handle and secured thereto

45 by screws or equivalent fasteners 42. The plate has a notch cut out in one corner so that the marginal edge portions may be keyed in grooves provided therefor in cooperating surfaces of the base. The plate not only

50 supports the cylinder or sheath and plunger rod it also serves as a support for the disk-like gear 44. This gear is bolted and pivoted in place as at 46 and approximately a three-quarter edge portion thereof is provided with gear teeth 48 which mesh with rack teeth 50 provided on the

55 coordinated surface portion of the plunger rod. Therefore, the plunger means may be said to be operated by rack and pinion means or more specifically by a rotatable handle-operated gear having teeth meshed with teeth on the projectible and retractile plunger rod. Incidentally, 60 the nose 52 (FIG. 2) of the rod is such that it registers with requisite nicety with the aligned end of the hinge pintle 18.

Although the gear operating handle may be of some other construction it preferably comprises a rod member 54 having a loop-like hand-grip 56 at an outer end. The other end portion is laterally offset at 58 where it is fashioned into a suitable foot 60, said foot fitting into a radial groove 62 and being suitably welded or otherwise secured in place. Obviously by rocking this gear handle or lever back and forth the gearing means is brought into play to properly actuate the plunger.

The numeral 64 designates a horizontal plate with the

marginal flange 66 which said plate screwed or otherwise fastened in place as at 67. This flanged plate provides a tray which functions to trap or catch the dislodged pintle as shown in FIGS. 1 and 2. The central portion of an edge of the plate is notched as at 68 so as not to interfere with the operation of the device.

In practice the channel of the channel-shaped base is lined up with the leaves 8 and 10 of the hinge means 6 as shown in the drawing. The channel is such in cross-section that the connected ends of the leaves 8 and 10 are covered thereby. However, it is necessary to shift the handle and the channel so that the notches 26 and 28 line up with the hinge knuckles 16 and 17 and the associated hinge pintle 18 in the manner clearly illustrated. All that is necessary now is to hold the base in position with the use of the outstanding handle 39 and to then operate the gear 44 by way of the lever or handle 54 to transmit motion to the plunger rod 34 by way of the cooperating gear and rack teeth. The nose 52 of the rod engages the registering pintle as is clear in FIG. 2 and the pintle is pushed out (in the manner depicted in FIG. 1) and trapped in the tray 64.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A portable manually usable mechanical hinge pintle dislodging and ejecting device comprising an elongated heavy base channel-shaped in cross-section with the channel open at ends thereof and with the median portions of the respective longitudinal walls of said channel provided with clearance notches, said notches registering with each other, said channel being adapted to be placed over the leaves of a butt-hinge so that the said notches register with the usual pintle-connected knuckles of said hinge, a handle disposed at right angles to a surface of said base opposite to the channel portion of the base, the axis of said handle being at right angles to the lengthwise axis of said base, a plate disposed in a plane parallel to the axis of said handle, said plate having marginal portions joined to the handle and to adjacent cooperating surfaces of said base, a plunger slidingly mounted on said plate, said plunger being in line with the aforementioned clearance notches and having an end portion 50 projectible into at least one of said notches when the plunger is being used, said plunger having rack teeth, a pinion gear parallel to and mounted for rotation on a surface of the plate, the teeth of said pinion gear being aligned and in mesh with the teeth on said plunger rod and a lever connected at one end to said gear and located in a position for movement in a path toward and from said handle.

position of the plunger, the teeth on said pinion gear being in mesh with the teeth in said rack, and a lever connected at one end to said gear and located in a position for movement in an arcuate path toward and from said handle.

2. The structure according to claim 1 and in combination, a tray suitable for trapping and temporarily retaining the aforementioned hinge pintle after it has been fully ejected, said tray having a bottom perched and secured on an upper edge of said body and being provided on marginal edge portions with upstanding marginal pintle confining flanges, a median portion of one edge of said bottom having a notch therein in communication with an adjacent one of the aforementioned clearance notches.

3. A portable manually usable mechanical hinge pintle dislodging and ejecting device comprising, in combination, an elongated base having a lengthwise face provided with an open-ended channel, median portions of the respective longitudinal walls of said channel being provided with aligned clearance notches, said channel being adapted to be registered with and placed over the leaves of a butt-hinge with the clearance notches registering with the usual pintle-connected knuckles of said hinge, a handle having an end thereof attached to said base intermediate the respective ends of the base and on a side thereof opposite to that side embodying said channels, a plate having an edge portion secured to said handle and having marginal edge portions resting firmly on and fixed to cooperating surfaces of said base, said plate being disposed in a plane at right angles to the lengthwise dimension of said base, a cylindrical sheath fixed across an exterior of said plate, a plunger rod reciprocable in said sheath, said plunger rod being in line with the clearance notches and having an end portion projectible into at least one of said notches in a manner to be lined up with and to engage the pintle which is to be dislodged and ejected from said pintle-connected knuckles, said plunger rod having rack teeth exposed and accessible through an opening provided therefor in said sheath, a pinion gear parallel to and mounted for rotation on a surface of the plate, the teeth of said pinion gear being aligned and in mesh with the teeth on said plunger rod and a lever connected at one end to said gear and located in a position for movement in a path toward and from said handle.
